UNITED STATES PATENT OFFICE.

GUSTAV J. KNAACK AND CHARLES J. MARQUARDT, OF PRINCETON, WISCONSIN.

WINDOW-SCREEN.

1,213,213.

Specification of Letters Patent.

Patented Jan. 23, 1917.

Application filed March 28, 1916. Serial No. 87,297.

To all whom it may concern:

Be it known that we, GUSTAV J. KNAACK and CHARLES J. MARQUARDT, citizens of the United States, residing at Princeton, in the county of Green Lake, State of Wisconsin, have invented certain new and useful Improvements in Window-Screens; and I do hereby declare the following to be a full, clear, and exact description of the invention, 10 such as will enable others skilled in the art to which it appertains to make and use the same.

This invention relates to window screens, and particularly to that type commonly 15 called extension screens, which are adapted for insertion in window frames of various widths.

The primary object of the invention is to provide a screen of this type which may be 20 readily extended or contracted, and wherein flies and other insects will be prevented from entering the room through the overlapping portions of the screen fabric.

A further object of the invention is to 25 provide a screen of this character which is of simple and inexpensive construction, which is composed of but few readily assembled parts, all so arranged as to prevent breakage or derangement of the screen, and 30 which will prove durable and thoroughly efficient in practice.

With these objects in view, together with others which will appear as the description proceeds, the invention resides in the novel 35 combination and arrangement of parts, all as will be described more fully hereinafter, illustrated in the drawings and particularly pointed out in the claims.

The invention will be best understood by 40 reference to the accompanying drawings, wherein:

Figure 1, is a front elevation of a screen embodying our invention, Fig. 2, is a sectional view taken on line 2—2 of Fig. 1, 45 Fig. 3, is a longitudinal sectional view taken on line 3—3 of Fig. 1, Fig. 4, is a detail perspective view of one of the connecting bars for the screen frame, and Fig. 5, is a similar view of the connecting strip.

Referring now more particularly to the drawings, 6 indicates the end members or stiles of the screen frames, to the extremities of which are connected the side members 7, the latter extending inwardly from the end 50 stiles in parallel relation. Two of the members or frames thus provided are employed

in the construction of each screen, the side members of each frame overlapping each other and are slidably connected. Each of the side members 7 of one frame is provided with a longitudinally extending groove, 60 within which a bead or rib 8 secured to the adjacent side member of the other frame fits, whereby the said frames may freely slide with relation to each other and will be prevented from lateral movement. The inner edges of each of the side and end members is 65 grooved as shown for the reception of the edges of the screen fabric 9, the latter being secured within each of the frames by means 70 of nails or tacks.

The free extremities of the respective frames are connected by a strip 10. This strip is formed of a sheet of relatively narrow metal bent or folded upon itself as 75 shown, the folded metal being then bent adjacent its lateral edges into substantially U-shape. The ends of the strip are inserted in the grooves in the opposite side members, and the screen fabric edge is inserted between the surfaces of the bent metal to be 80 securely held therein. The ends of each strip may be secured to the side members by tacks or nails 11. The bent portion of each strip extends inwardly slightly beyond the 85 inner faces of the side members to engage and rest upon the wire fabric of the adjacent screen frame, and by reason of the rounded edges present upon the bent portions of the strip it will be obvious that sliding movement of the screen fabric from the said 90 strips will be permitted without danger of the fabric becoming broken or torn by the said strip. It will be understood that the inwardly extending portion of each strip is 95 coextensive with the length of the latter, and engages with the adjacent face of the screen fabric of the opposite frame throughout the width of the latter.

To securely hold the screen fabric of each 100 frame against bulging, and to prevent insects from gaining access to the room between the overlapping sections of the screen fabric, a connecting bar 12 is provided for each screen frame. This bar comprises an 105 elongated metallic member bent upon itself longitudinally as shown to provide rounded corners, the said bar being of a length equal to the distance between the inner edges of the opposite side members 7 of the frames. 110 A connector plate 13 is secured to the opposite ends of each connecting bar, and extends

over the outer faces of each of the side members 7. The connector plates may be bent as at 14 inwardly so that the bar will rest snugly against the fabric of the adjacent 5 sliding section. Each of the connecting bars 12 is arranged directly over the strip 10 with which it travels, the said bars and strips being spaced apart a distance sufficient to permit of the free sliding movement 10 of the screen fabric of the opposite frame and it will be seen that the screen fabric of the slideable frames is thus held against bulging to prevent insects passing beyond the screen end and into the room. A clip member 15 is secured to each of the side members 7 of the frames, the said clips extending through elongated slots 16 in the overlapping sides of the adjacent screen section and are connected at their ends to the connector 20 plates 13, the extremities of the said clip members being bent outwardly as shown to secure the said connector plates thereto. It is thus seen that the strips 10 and bars 12 of each section are held firmly in proper position, and the screen frames are free to 25 slide one upon the other.

While we have herein shown and described a particular or preferred embodiment of the invention, we desire to have it understood that we need not confine ourselves to all the precise details of construction herein set forth by way of illustration, as modification and variation may be made without departing from the spirit of the invention or exceeding the scope of the claims.

What is claimed is:

1. A window screen comprising two similar frames composed of parallel overlapping side portions each connected at one end by 30 an end member, screen fabric stretched across each of said frames, a strip connecting the free ends of each frame and the adjacent lateral end of said fabric, the said strip of 40 each frame being bent inwardly throughout its length to engage the adjacent surface of 45 the fabric of the opposite frame, and a con-

necting bar connecting said side members of each frame upon the opposite surface of the fabric of the opposite frame to force the said fabric into engagement with its corresponding strip, substantially as described. 50

2. A window screen comprising two similar frames composed of sliding parallel overlapping side sections each connected at one end by an end member, each side portion being provided with registering elongated slots, screen fabric connecting the ends of each frame and supporting the adjacent edge of the screen fabric, a bar connecting the ends of each of said frames and engaging the fabric of the adjacent frame, clips securing the ends of each bar to its respective frame and passing through the slot in the next adjacent frame side member, substantially as described. 55

3. A window screen comprising two similar frames composed of parallel overlapping side portions each connected at one end by an end member, the said side portions and end members being provided with 70 grooves, wire fabric stretched across each frame and engaged at its edges in said grooves, a strip connecting the free ends of each frame, each strip comprising an elongated metallic member arranged at its ends in said grooves and bent longitudinally to provide clamping portions for the reception of the end of said screen fabric, the said strip extending laterally to engage with the fabric of the adjacent frame throughout the 75 width of the latter, and a bar connecting the ends of each frame and engaged throughout its length upon the opposite side of the adjacent frame fabric and over said strip, substantially as described. 80

In testimony whereof, we affix our signatures, in the presence of two witnesses.

GUSTAV J. KNAACK.

CHARLES J. MARQUARDT.
